[57] ABSTRACT

In a method of detecting breaks in an insulated electric conductor or other flexible elongate member whose surface is of an insulating material capable of generating an electrostatic charge by friction with another surface, the member travels in the direction of its length past and in continuous contact with at least one electrode which is connected to earth or some other charge sink. The electrode (or each electrode) is conductive and of a material chosen to cause electrons to be transferred continuously in one direction between the electrode (or each electrode) and the surface of the member and electrons are caused to flow between the charge sink and the electrode (or each electrode) or vice versa; the current flowing between the electrode or electrodes and earth is continuously monitored, preferably using an amplifier connected across a resistor between the electrode or electrodes and the charge sink.

DETECTION OF BREAKS IN FLEXIBLE ELONGATE MEMBERS

This invention relates to the detection of breaks in the continuity of a material as the material travels past a detecting region. The material may be in the form of an elongate article that travels past the detecting region in the general direction of its length or it may be in the form of a stream of intercontacting particles of the material, for instance powdered or granular material. Such elongate articles and streams of particles will hereinafter, for convenience, be included in the generic expression 'flexible elongate member'.

The invention is especially, but not exclusively, concerned with the detection of a break in a flexible elongate member which for instance might be one insulated conductor, or a pair of insulated electric conductors. The invention is also applicable to the detection of breaks in single threads or strings, or other single or composite flexible elongate members, for example, tapes or webs or streams of particles.

In the manufacture of an electric cable comprising a multiplicity of single conductors or pairs of insulated conductors of small diameter, for example a telephone cable, one of the problems that cable manufacturers are continuously seeking to overcome is that of the detection of breaks in one insulated conductor or a pair of conductors during manufacture of the cable before twinning or before a multiplicity of pairs are assembled together and sheathed. If breakage in such flexible elongate member is not detected especially until after the pairs have been assembled together and a continuity test effected, either the cable must be repaired with considerable difficulty and not inconsiderable expense or the cable must be accepted with a reduced complement of effective pairs or quads.

The present invention has for its principal object the provision of a simple and cheap method of detecting breaks in a flexible elongate member, whose surface is of an insulating material capable of generating an electrostatic charge by friction with another surface.

According to the invention the method comprises causing the member to travel in the direction of its length past and in continuous contact with at least one electrode which is connected to earth (which expression as used herein includes any charge sink). The electrode, or each electrode if there is more than one, is conductive and of a material chosen to cause electrons to be transferred continuously from the electrode (or each electrode) to the surface of the member or vice versa and electrons are caused to flow from earth to the electrode (or each electrode) or vice versa. In choosing the electrode material, the material of the surface of the member is a relevant factor. Current flowing between the electrode or electrodes and earth is continuously monitored, an interruption in said current flow indicating the occurrence of a break in the member. The surface of the elongate member may either be electrostatically charged by contact with appropriate surfaces as is frequently the case in textile and cable making machinery before it reaches the electrode or electrodes or it may be charged by frictional contact with the electrode or electrodes.

Preferably the electrode (or each electrode) is connected to earth through a high value resistor, hereinafter referred to as the detector resistor, and the current flow and hence the continuity of contact between the

travelling member and the electrode or electrodes is continuously monitored by observing the voltage across the detector resistor.

By applying a dc voltage to the electrode or electrodes the flow of electrons due to continuous contact between the travelling member and the electrode or electrodes can be increased, the direction of flow depending on the polarity of the voltage.

Where the member or each of the members is an insulated conductor we have found that even with a voltage of say -50 V dc the flow of electrons to the surface of the insulated conductor or each of them can be appreciably increased. However, with a view to avoiding spurious effects otherwise caused to the current flow by bare portions of the insulated conductors, and especially in the case of paper insulated conductors where the surface condition of the paper may be variable, we prefer to apply a voltage of about -200 V dc to the electrode or electrodes.

The invention also includes apparatus for use in the method of the invention, which apparatus comprises at least one electrode having a surface of a material capable of generating an electrostatic charge on the member or discharging an electrostatic charge from the member and of such a form that a flexible elongate member can be caused to travel in the direction of its length past and in continuous contact with the electrode or electrodes; a resistor connected in series between the said electrode or electrodes and earth; and means for continuously monitoring current flow between the said electrode or electrodes and earth.

Preferably the apparatus also includes an amplifier connected across the resistor, the monitoring means being connected to, and adapted to measure the voltage output of, the amplifier. If desired a source of dc voltage may be connected between the resistor and earth.

The invention will be further illustrated by a description, by way of example, of preferred apparatus for continuously monitoring insulated conductors for breaks, with reference to the accompanying drawings in which:

FIGS. 1-3 show diagrammatic representations of three forms of apparatus in accordance with the invention, and

FIGS. 4-7 show a practical form of apparatus for use in the manufacture of multiconductor cable.

The apparatus shown in FIG. 1 comprises three elongate steel electrodes 1, each in the form of a steel rod mounted on and projecting from a support 2 of insulating material with their axes substantially parallel one with another. The axes of two of the electrodes 1 lie in a common horizontal plane and the third electrode is spaced between these two electrodes and above the common plane of their axes and is adjustable and/or resiliently mounted for movement in a substantially vertical direction to accommodate conductors or conductor pairs of different overall diameters passing in continuous contact between the electrodes as indicated. The electrodes 1 are connected in series to earth through a resistor 3 of 50 M and a resistor 4 of 10 M. Connected across the resistor 4 is a shielded amplifier 6 to the output of which is connected a detector 7.

FIGS. 2 and 3 respectively show diagrammatically the use of positive and negative dc sources 8 and 9.

In some circumstances it may be advantageous to dissipate the charge on the travelling member after it has

passed the electrode and FIGS. 1 and 2 show diagrammatically a positively charged member 10 for this purpose.

FIGS. 4 and 5 illustrate a practical form of electrode assembly for use in monitoring the movement of a large number of pairs of insulated wires 11 advancing parallel to one another towards the point where they are to be stranded together. The stainless steel electrode rods 1 are 9.5mm in diameter and long enough to accommodate any anticipated lateral movement of the wire pairs. For each wire pair there are two fixed electrode rods 12, mounted in an acrylic ("Perspex") panel 13 which is 25mm thick, engaging the underside of the wire pair and a single central adjustable electrode rod 14 mounted in a slideable acrylic rod 15 and passing through a clearance hole in the panel 13 so that the pressure between the electrode rods 12, 13 and the wire pair 11 can be adjusted by a screw 17 to accommodate conductor pairs with different dimensions and/or different flexibilities.

FIGS. 6 and 7 show a suitable electrical circuit designed so that it can be arranged, if desired, to give an output alarm signal only if the number of broken pairs exceeds a predetermined acceptable level.

Each group of electrode rods 1 is connected by a screened cable to an individual primary amplifier unit 18 (FIG. 6) only one of which is shown in detail. The input current is taken through resistors R1 (100M) and R2 (10M) to the local voltage reference on line 23 which is -200V with respect to earth and to which all screens are connected.

Transient currents are shunted by a by-pass capacitor C1 (2.2n). The signal current flowing through R1 is typically of the order of 1 nA and to ensure effective response, the amplifier A1 must have an input impedance large compared with R2 and an input bias current small compared with the signal current. An operational amplifier with an F.E.T. (Field Effect Transistor) input is available from Burr-Brown Research Corp., of International Airport Industrial Park, Tucson, Arizona, or from Burr-Brown International of 25A King Street, Watford, Hertfordshire, England, and has been found satisfactory. This has an input impedance of 10^{13} ohm and 3 pF and an input bias current not exceeding 25pA at 25°C (doubling for each 10°C temperature rise).

The amplifier input is protected against overvoltage by diodes D1-D2 (type PAD 1) and the gain of the amplifier determined by a voltage divider R3 (1M), R4 (1K), resistor R (10M) being selected to minimise the input offset due to bias current and noise. Variable resistor RV1 (10K) is adjustable to set the input offset to zero, and capacitor C (5pF) inhibits oscillation at the cross-over point of the amplifier. R5 (45K) is the load resistor of the amplifier and diode D3 (type 1N 914) ensures that only positive outputs can be fed to the line 19. Here and elsewhere in the circuit diagrams power supply input is indicated simply by terminals 20.

Owing to the stochastic nature of the electrostatic charge-transfer process, the output at line 19 varies unpredictably within a range of positive values, and to allow meaningful summation of the signals relating to the separate wire pairs, it is next converted to a substantially constant value by a logic gate L. A solid-state device is preferred, although it would be possible in principle to use a relay. In particular, the solid-state logic device sold by RCA International Ltd of 50 Curzon Street, London W1 as the Cosmos Exclusive-OR

gate is preferred. The output voltage signal from the logic gate L when the voltage on line 19 is substantially different from the local voltage reference (line 21) is constant (to an accuracy better than the reciprocal of the number of wire pairs being monitored) and does not vary with the magnitude of the input voltage in its working range. If the input signal disappears the output falls to zero (to the same degree of accuracy).

The logic output signals in respect of all the wire pairs are summed by a resistance network comprising individual resistors R6 (22K) and a common resistor R7 (270) to obtain at 22 an output signal voltage which varies linearly with the number of input signals: on failure of any individual input signal, the corresponding R6 is effectively placed in parallel with R7, drawing additional current from the other logic devices and so producing an enlarged voltage drop across the other R6's and reducing the voltage across R7.

Referring now to FIG. 7, the output signal from the part of the apparatus shown in FIG. 6 is amplified by amplifier A2 and fed to upper and lower limit comparators Co1 and Co2, respectively. Reference signals dependent on the number of wire pairs being stranded are derived from a switched potential divider network comprising a double-pole decade switch S1 controlling two series of ten 100-ohm resistors R8 and setting tens of conductor pairs and a single pole decade switch S2 controlling a single series of ten 1K resistors R9 and setting units of conductor pairs. Resistors R10 are selected to ensure an appropriate input voltage range for the amplifier A3 which supplies an upper-limit signal to the comparator Co1 and also a related lower-limit signal via a network comprising amplifier A4 to comparator Co2. The relation between the upper and lower reference signals, which determines the number of broken pairs that will be tolerated, may be made adjustable if desired by using variable components in the network of amplifier A4. Amplifiers A2-A4 may all be of the kind sold by National Semiconductors Corp of 2900 Semiconductor Drive, Sante Clara, California, or from National Semiconductor (UK) Ltd of the Precinct, Broxbourne, Hertfordshire, England as type LM 301A and the comparators Co1 and Co2 may be of the type sold by Burr-Brown Research Corp and by Burr-Brown International (whose addresses are given above) as type 4082/03.

Appearance of an output signal from Co1 indicates that the number of wire pairs detected exceeds the number set on the decade switches (normally due to a setting error), whereas an output signal from 2 indicates that the number of pairs detected is lower than the set number by more than the built-in (or pre-set) tolerance.

In normal operation, any output signal from either of the comparators is fed to a relay Re 1 which closes contacts Re 1/1 to illuminate an alarm lamp L1 energised from a tertiary winding of the mains transformer T. The relay Re 1 also closes latching contacts Re 1/2 to maintain itself energised from the power supply for comparator Co1 until re-set by the normally-closed manual switch S3. The relay Re 1 may have additional contacts Re 1/3 for operation of a machine-stop control.

To avoid difficulties in starting, the relay Re 1 is only connected by a second relay Re 2 in turn controlled by a centrifugal switch S4 when the cable stranding machine reaches a predetermined speed. An indicator

lamp L2 may be associated with this switching action, and a mains indicator lamp L3 may also be provided.

As already indicated in describing FIG. 6, the line 23 is maintained at -200 V with respect to earth; this voltage is established by the secondary of Transformer T in conjunction with Diodes D4 and a conventional resistance/capacitance smoothing network.

The apparatus shown in FIGS. 3-7 can be used to detect breaks in a pair of insulated conductors (telephone pair) each having a conductor diameter as low as 0.3mm and conventional thickness of insulation and can be operated at speeds down to approximately 5 metres/minute.

The invention has the important advantages that it is simple, provides a quick response on the detection of a break and is dependent on linear movement of the flexible elongate member and neither on rotational movement of a guide or carrier therefor, nor on the loss of tension at the detection point. The apparatus of the invention can be accommodated in the fixed input system in a pairing, quadding, stranding, cabling or other cable-making machine without any necessity to effect any substantial modification to the machine.

What we claim as our invention is:

1. A method of detecting breaks in a flexible elongate member whose surface is of an insulating material capable of generating an electrostatic charge by friction with another surface comprising causing the member to travel in the direction of its length past and in continuous contact with at least one electrode which is connected to a charge sink, said electrode being conductive and of a material chosen to cause electrons to be transferred continuously in one direction between said electrode and the surface of said member and to flow between the said charge sink and said electrode, and continuously monitoring the current flowing between said electrode and said charge sink to observe whether it falls below a predetermined value.

2. A method in accordance with claim 1 comprising applying a dc voltage with respect to the said charge

40 45 50 55 60 65

sink to said electrode.

3. A method of detecting breaks in an insulated electric conductor whose surface is of a material capable of generating an electrostatic charge by friction with another surface, comprising causing the insulated conductor to travel in the direction of its length past and in continuous contact with at least one electrode which is connected to a charge sink, said electrode being conductive and of a material chosen to cause electrons to be transferred continuously in one direction between said electrode and the surface of said insulated conductor and to flow between the said charge sink and said electrode, and continuously monitoring the current flowing between the said electrode and said charge sink to observe whether it falls below a predetermined value.

4. A method of detecting breaks in an insulated electric conductor whose surface is of a material capable of generating an electrostatic charge by friction with another surface comprising causing the insulated conductor to travel in the direction of its length past and in continuous contact with at least one electrode maintained at a fixed dc voltage with respect of a charge sink, said electrode being conductive and of a material chosen to cause electrons to be transferred continuously in one direction between said electrode and the surface of said conductor and to flow between the said charge sink and said electrode, and continuously monitoring the current flowing between said electrode and said charge sink to observe whether it falls below a predetermined value.

5. A method as claimed in claim 4 in which said voltage is at least 50 volts.

6. A method as claimed in claim 4 in which said voltage is about 200 volts.

7. A method as claimed in claim 3 comprising connecting said electrode to earth through a high-value detector resistor and observing the voltage across said detector resistor.
